G. H. SPAULDING.

Harvesters.

No. 140,738.

Patented July 8, 1873.

UNITED STATES PATENT OFFICE.

GEORGE H. SPAULDING, OF ROCKFORD, ILLINOIS.

IMPROVEMENT IN HARVESTERS.

Specification forming part of Letters Patent No. 140,738, dated July 8, 1873; application filed November 6, 1872.

To all whom it may concern:

Be it known that I, GEORGE H. SPAULDING, of Rockford, in the county of Winnebago and State of Illinois, have invented certain new and useful Improvements in Harvesters; and I do hereby declare the following to be a full and exact description of the same, reference being had to the accompanying drawings forming part of this specification, in which—

Figure 1 is a plan view of the machine; Fig. 2, an elevation of its front side; Fig. 3, an elevation of the binder end of the machine; Fig. 4, a detached plan of the convertible tongue; and Fig. 5, a transverse vertical section, showing the mechanism which drives the cutter-bar.

Similar letters of reference in the accompanying denote the same parts.

This invention belongs to that class of harvesters which are drawn by one horse, the driver of which is also the binder of the grain. The invention has for its object to improve the construction of machines of this class so as, first, to prevent the heads of the straw from traveling faster along the back side of the horizontal apron that conveys it to the elevator than the butts travel along the front side; second, to afford a clear space for the passage of those ends of the straw that project beyond the elevator, and at the same time to prevent the straw from falling backward while being carried upward by the elevator; third, to allow the machine to be raised or lowered without slackening or tightening the band that drives the elevator; fourth, to enable the driver to conveniently stand facing the horse, manage with his foot the apparatus by which the horse is guided, and discharge the gavels with his hands. To these ends the invention consists, first, in a serrated extension-board placed at the rear side of the horizontal apron which first receives the cut grain, on which board the heads of the straw fall, and by which they are prevented from traveling faster than the stubble ends; second, in a press-board supported at its front side by means of an arm extending from the front end of the elevator-frame around in front of it, said press-board having, also, serrations in its inner side next the elevator; third, in the arrangement of a wheel which

at once transports the elevator-frame and drives a band-wheel, and is itself mounted in a lever, with the elevator-shaft operated by the band, and with tension-wheels applied to the band; fourth, in a vibratory shaft having a head piece to fasten the reins to, and a foot piece by means of which the driver can operate the shaft; all which I will now proceed to describe.

In the drawing, A is the extension-board, the same being attached by screws passing through slots *a* in the board into the back bar of the apron-frame B. The board A has a row of serrations, *b*, along its front edge. It is well known that the heads of grain tend to travel faster on the apron than the stubble ends, the consequence of which tendency is that the straw presents itself to the binder diagonally, and has, therefore, to be straightened before being bound. The function of the serrations *b* is to obviate this tendency by obstructing the motion of the heads, and thus to cause the grain to present itself straight to the binder. C is the canvas apron running over rollers placed one at each end of the frame B. The straw is taken off from the apron C by an elevator consisting of a series of inclined bands, *c*, armed with teeth *d*, and running over a lower roller, D, mounted in the frame B, and an upper roller, E, mounted at the top of a frame, F. In front of this frame is a float or press-board, consisting of a series of parallel bars, *e*, bound together by top and bottom cross-boards *h*. This device answers the ordinary purpose of press-boards, viz., to press the straw as it is carried upward on the teeth of the elevating-bands. In narrow machines like this one, where the straw is long, the heads often extend beyond the rear side of the frame, and it is therefore important to the proper formation of the gavels that these projecting ends should be as clear of impediment in their progress as is that part of the straw which does not project. Accordingly the press-board is hung to a sickle-shaped arm, G, whose butt is fastened to the front end of the frame F, and which extends around in front of the press-board. Links *i*, whose upper ends are jointed to the arm G, and whose lower ends to the bottom cross-board *h*, serve to suspend the press-

board to the arm. As the stubble ends of the straw do not project beyond the frame F, the arm G does not stand in their way, and by its location it is removed from any possibility of standing in the way of the projecting heads of the grain at the other end of the frame. The inner face of the bars e are notched in order to keep the straw, when in a mass thicker than the length of the teeth d, from falling down the elevator, as it would otherwise be liable to do when the machine passes over rough ground, the press-board being necessarily hung loosely. The transporting-wheel H is mounted on a lever, I, the front end of which is jointed to the front end of the frame F. On the shaft of the transporting-wheel at the other side of the lever I is placed a band-wheel, J, from which the band K runs forward to tension-wheels k mounted on a bar attached to the front end of the frame F. Passing around the tension-wheels, the band runs up to a sheave, l, placed on the front end of the shaft of the upper elevator-roller E.

By raising or lowering the rear end of the lever I the frame F is lowered or raised, as may be required, and this without tightening or slackening the band K, the distance of the band-wheel J from k, the center of motion, being neither increased nor diminished during any movement of the frame F.

On the shaft of the upper roller E is secured an eccentric, l', the strap m of which is fastened to the upper end of a pitman, n, the lower end of which is jointed to the upper end of an elbow-lever, o, whose lower end is jointed to the sickle-bar p. Hence the sickle-bar is immediately reciprocated by the rotation of the roller E. The lower roller is driven by the bands c, and is itself the motor of the apron C, being connected with the nearest roller thereof by a belt, q.

It will be observed that the spaces between the bars e form continuous slots lengthwise of the press-board. In these slots run the independent bands c of the elevator, the bars e serving to hinder the teeth d from turning over sidewise, and running under the grain without carrying it up.

The grain is discharged by the elevator into the receiver L, and there bound. The outer edge of the receiver is made slanting inward from front to rear. This inclination of the receiver L enables the binder, who is also the driver, to stand partly facing the horse, and in a convenient position for observing it. At the same time the width of the table to the left of the binder is diminished so that he can discharge the gavels from the machine with greater ease than as though the table were not inclined.

In the front end of the platform N a vertical shaft, O, is loosely stepped, so that it can vibrate, and to the bottom of this shaft a piece, P, is attached, by means of which the driver can vibrate the shaft with his foot. To the head of the shaft a cross-piece, R, is secured, which has eyes r, to which the reins are to be fastened. Hence, by vibrating the shaft with his foot, the binder can guide the horse without using his hands at all. A bar, T, is pivoted at one end to a lug, s, springing from the lever I just over the axle of the transporting-wheel. This bar passes forward past the upright part of the frame F, into which extends a screw occupying a slot in the bar. To the front end of the bar T a cross-bar, t, is attached, and to the ends of the cross-bar t the thills V are fastened. The rear ends of the thills are connected by plates v with the bar T in rear of the cross-bar t.

By removing the screws that connect the thills with the cross-bar the thills can be drawn forward, turning the plates forward against the bar T, and bringing the points of the thills together, as shown in Fig. 4, thus forming a tongue. Hence this machine can be adapted to be drawn by a pair of horses as well as by a single horse.

What I claim as new is—

1. A serrated extension board, placed at the rear of the horizontal apron, and designed to prevent the heads of the straw from traveling faster than the stubble-ends, substantially as described.

2. The press-board e h, hung to the arm G, and attached only to the front side of the machine, in the manner described, and for the purpose of preventing the projecting heads of the straw from being obstructed while being elevated.

3. The press-board e h, serrated on its inner face for the purpose of preventing straw from falling while ascending the elevator, substantially as described.

4. The combination of the elevator-frame with the lever I, transporting-wheel H, band-wheel J, band K, tension-pulleys k, and elevator-roller E, arranged as described, for the purpose of raising and lowering the machine without slackening the band.

5. The vertical shaft O, having a foot-piece, P, and head-piece R, for the purpose of enabling the binder to guide the horse with his foot, substantially as specified.

GEO. H. SPAULDING.
